PROTECTIVE SLEEVE FOR RESISTOR
CONNECTER DEVICEAnthon A. Leonard, Glenside, Pa., assignor to
Philadelphia Storage Battery Company, Phila-
delphia, Pa., a corporation of Pennsylvania

Application January 13, 1932, Serial No. 586,389

5 Claims. (Cl. 201—63)

This invention relates to protective devices for connectors and has particular reference to devices of the class disclosed and claimed in a co-pending application of John M. Bowman, Serial No. 586,396 filed Jan. 13, 1932. Such co-pending application discloses a resistor connector device particularly adapted for use in connection with motor vehicles equipped with radio receivers. The chief object of the present invention is to provide a sleeve for use in connection with such devices to mechanically and electrically protect the same, thereby eliminating the possibility of short-circuit due to the accumulation of dirt, oil or other foreign substance, while providing mechanical security for the terminal connections.

The following description and the accompanying drawing discloses the invention as applied to the particular form of device forming the subject matter of the above-mentioned co-pending application. It is to be understood, however, that the invention is thus not limited in scope but is capable of general application. In the drawing:

Fig. 1 is a schematic illustration of a suppressor or resistor device in connection with the associated parts of a motor vehicle equipped with a radio receiver; and

Fig. 2 is a sectional view clearly illustrating the invention.

Without limiting its applicability, the invention is illustrated herein as applied to the specific device for which it is intended, as indicated above. For the purpose of the present description, it suffices to state that suppressor resistor elements are interposed in the spark plug lead or supply conductor of a motor vehicle equipped with a radio receiver, the purpose of the resistor being to prevent disturbances originating in the ignition system of the vehicle from interfering with the normal operation of the radio receiver. Fig. 1 illustrates this arrangement clearly, wherein 1 designates the usual cylinder head of a motor vehicle. 2 designates a spark plug thereof. 3 and 4 are sections of the spark plug conductor, and 5 is the suppressor resistor element with the novel device of the invention applied thereto.

Referring to Fig. 2, wherein the invention is illustrated in detail and the elements in Fig. 1 have been given like reference characters, the suppressor resistor is shown at 6 and takes the usual cylindrical form of such elements. In accordance with the Bowman device, mechanical and electrical connection of conductor sections 3 and 4 is made to the ends of terminals of element 5. To this end, a pointed screw 7 having

sharp threads is attached to each end of the resistor element. Preferably, the screw resembles an ordinary wood screw, and a cup-shaped retainer 8, which may be made of brass, serves to retain the screw by engaging the flanged head 9 thereof. The shank of the screw extends through the apertured opening 10 in the bottom of retainer 8. The retainer is of such dimension that the end of the resistor element fits nicely therein. Preferably, a layer of steel wool 11 or other conductive spring is interposed between the head of the screw and the resistor element. A binding of cement 12 or like substance serves to attach retainer 8 to the resistor element securely. It will be understood that both ends of the device 15 are formed as described.

As illustrated clearly in Fig. 2, the usual insulated stranded conductor used for spark plug conductors and other purposes may be readily connected to the device by merely screwing the 20 threaded shank of screw 7 into the end of the stranded conductor longitudinally thereof. The individual strands of the conductor interlock firmly with the screw threads to provide a very efficient mechanical and electrical connection.

In accordance with the present invention, in order to enhance the efficiency of operation of the device described above, I provide a protective sleeve 13 which may be formed of any suitable insulating material such as porcelain. This sleeve is of such internal diameter that it closely encircles the assembled elements and it is of such length that it completely covers the resistor element as well as the electrical joints or connections. The sleeve is preferably applied before cement 12 hardens so that the cement firmly adheres to the internal surface of the sleeve and thus secures it in position. It is further to be noted that screw 7 expands the conductor and its insulation, thus jamming or wedging the insulated conductor in the sleeve. This enhances the efficiency of the device from the standpoint of electrical connection and mechanical security.

Obviously, the sleeve completely shields the various elements from the accumulation of foreign substances which might otherwise detrimentally affect the operation by causing a short circuit or at least a by-pass of relatively low impedance about a resistor. The sleeve also enhances the appearance of the device and makes it mechanically stronger as will be obvious.

The construction of the sleeve may, of course, be modified in details and it is to be understood that only the limitations contained in the appended claims are to limit the invention.

I claim:

1. A resistance device comprising an impervious tube of non-conducting material, a resistance element in said tube, an insulated conductor fitted into an end of said tube, metal terminals carried by the tube and in electrical contact with the respective ends of said element, one of said terminals comprising a member recessed to receive an end of said resistance element and having a tapering axial projection for engagement with the conducting core of said insulated conductor fitted into an end of the tube, whereby the insulation of said conductor may be wedged against the tube inner wall to form a moisture proof seal therewith. 10
2. A resistance device comprising an impervious tube of non-conducting material, a resistance element in said tube, an insulated conductor fitted into an end of said tube, metal terminals carried by the tube and in electrical contact with the respective ends of said element, one of said terminals comprising a member recessed to receive an end of said resistance element and having a tapering axial projection for engagement with the conducting core of said insulated conductor fitted into an end of said tube to wedge the insulation of the conductor against the inner tube wall to form a moisture proof seal therewith, said metal terminal being cemented into an end of said tube. 15
3. A resistance device comprising an impervious tube of non-conducting material, a resistance element in said tube, an insulated conductor fitted into an end of said tube, metal terminals carried by the tube and in electrical contact with the respective ends of said element, one of said terminals comprising a member recessed to receive an end of said resistance element and having a tapering axial projection for engagement with the conducting core of said insulated conductor fitted into an end of the tube, whereby the insulation of said conductor may be wedged against the tube inner wall to form a moisture proof seal therewith. 20
4. A resistance device comprising an impervious tube of non-conducting material, a resistance element in said tube, an insulated conductor fitted into an end of said tube, metal terminals carried by the tube and in electrical contact with the respective ends of said element, one of said terminals having a tapering axial projection for engagement with the conducting core of said insulated conductor fitted into an end of said tube to wedge the insulation of the conductor against the inner tube wall to form a moisture proof seal therewith, said one metal terminal at least being fixed in said tube. 25
5. The combination with an electrical element and a tapered member electrically connected thereto and insertable into an end of an insulated conductor, of a protective insulating sleeve closely encircling said element and extending along said tapered member, whereby said tapered member expands the insulation of said conductor and jams it against the inner wall of said sleeve. 30
